FOUR COLOR WEAVING LOOM

Tullio Ciarloni, Costamasnaga, Italy, assignor to Ateliers de Construction de Ruti S. A., Ruti Zurich, Switzerland

Application May 25, 1951, Serial No. 228,303

Claims priority, application Italy December 2, 1950

9 Claims. (Cl. 139—232)

The present invention relates to a four colours weaving loom wherein, on both sides thereof, there are mounted four boxes for receiving the corresponding shuttles, said boxes having mounted thereon means automatically changing spent shuttles.

It is known that in the conventional four colours weaving looms, there are four shuttle boxes on one side of the loom, and only one box on the opposite side. Therefore, when it is desired to change the colour of the shuttle, it is necessary to have such shuttle returned to the box which belongs to the set of four boxes, so as to make way in the single box on the opposite side, for the shuttle with the new colour it is desired to insert in the next weft.

This makes it necessary to insert for each colour an even number of weft picks due to the above mentioned necessity of always returning the shuttle to the same side before changing the colour. This necessity had to be kept in mind in designing new patterns for such looms and constituted a hindrance limiting the variety of the patterns.

The present invention avoids the above inconvenience inasmuch as it provides four shuttle boxes on each side of the loom so that the weft picks in any one colour may also be in an uneven number.

It is also an object of the present invention to provide a device for the automatic changing of the spent shuttles, said device being controlled by four feelers applied to the shuttles, at the side opposite the one on which there is provided the changing device.

The accompanying drawing illustrates in a very diagrammatical way and merely by way of an example, the characteristic devices of the present invention, that are applicable to looms otherwise of any known or preferred type.

In the drawing:

Figs. 1 and 2 illustrate, in a front and side view respectively, the device that controls the stopping of the loom and the starting of the shuttle changing.

Fig. 3 shows diagrammatically the shuttle changing mechanism which includes ensemble of cams and levers controlling the freeing of the shuttles to be changed in the inside of their respective box, as well as the members effecting the ejection of the spent shuttle, and the successive starting of the loom, upon said changing being completed and the cams and levers controlling the shuttle magazines for paying out a new shuttle to replace the spent one.

Fig. 4 illustrates a front view of the ensemble of the shuttle clamping blades or strips provided on the four shuttle boxes.

Fig. 5 is a plan view, from above, of a detail of Fig. 4.

Fig. 6 represents a detail of the shuttle transfer arm, and

Fig. 7 represents, in side view and in profile, a detail of the control lever for starting the loom.

The loom, according to the invention, is of standard construction and includes the usual and known members

2

of a weaving loom which, having no particular relation to this invention, are neither illustrated in the attached drawing nor described specifically in the following application. In the drawing, the shuttles are indicated at N; as shown in Figure 3. The shuttles are four in number, each carrying a thread of different colour, and can rest in one of the four shuttle boxes, on either side of the loom. In each of these boxes, the shuttles are frictionally arrested by means of blades or strips 20 (see Figs. 4 and 5) which resiliently press against the shuttles as the shuttles abut them. Said shuttles are then driven out for the return stroke by a conventional shuttle picking member, and when it is desired to replace a spent shuttle, the strips 20 are lowered to free the shuttle and drop it out from the respective box to make way for the new shuttle.

As has been said, the changing of the shuttle takes place automatically under electric control actuated by a feeler combined with each shuttle. Whenever such a placement is necessary, the loom is stopped for a few minutes until the different members, operated in sequence by reciprocal inter-action, and by the pull of an electromagnet, have performed the necessary substitution, whereupon the loom is automatically started again and the weaving takes place according to the predetermined pattern.

In Figs. 1 and 2 are illustrated the levers which are actuated by the electromagnet excited through the operation of the above mentioned feelers, and from these members are originated all the movements that effect the automatic changing of the shuttle. In said figures, there is clearly illustrated a lever 2, pivoted at 3 and connected by rod 4 with the slay driving members. On said lever 2, there is secured an electromagnet 1. Lever 2 swings in synchronism with the reciprocating movement of the slay. On each shuttle there are applied in a known way, feelers that signal when the shuttle is spent, by closing a circuit for exciting electromagnet 1. Upon energizing of said electromagnet 1, it pulls the rear extension of an arm 5, which then takes the position indicated in full lines in Fig. 2, while in its rest position, said arm drops to the position 5', shown in dotted lines. The swinging motion of lever 2 is translated to the arm so that when lever 2 snaps in the attracted position pulled by the electromagnet 1, the free end of said arm 5 will act on the left hand side (see Fig. 1) of a lever 6, mounted rotatably on shaft 7, and which on the other side carries fast two flexible Bowden type control cables 8, 9 extended in opposite directions. The rotation of lever 6 on shaft 7, actuated by arm 5, causes the slackening of cable 8, which brings about the stopping of the loom, while cable 9 is tensioned and closes a circuit (not shown) that sets in motion shaft 15, which, through a set of cams and levers operates the substitution of the shuttle, as described hereunder more in detail.

The stopping of the loom by effect of the slackening of cable 8 shall not be described as this operation is already known and applied in the conventional looms.

Lever 6 has an offset extension 6', extended downwardly and adapted to strike against a block 10 fast with shaft 7 which in turn is rigidly connected with another block 11. Said block 11 has an angle arm 12 protruding upwardly and on which there is fixed a manually operable loom stopping rod 13. That is, when it is desired to manually stop the loom, the rod 13 is turned to rotate the shaft 7 and therefore also block 10 and lever 6, enough to cause the slackening of cable 8 and the tensioning of cable 9, in the same way as the operation of arm 5.

The substitution of the shuttle takes place upon the control action, exerted by cable 9, which in any whatever known or preferred way, usually through an electric motor, causes the rotation of shaft 15, whereon there are keyed cams 63, 16, 27, 29, 60, 51 and 45. Each of

said cams actuates a corresponding lever which all, in combination with other members cause:

- (a) The release of the strips or blades 20 from the stationary shuttle boxes, so as to allow the free movement of the shuttle N to be substituted;
- (b) The ejection of the spent shuttle;
- (c) The actuation of the shuttle magazine for the extraction of the new shuttle, to substitute the ejected one;
- (d) The transfer of the new shuttle from the magazine to the box and
- (e) The starting again of the loom.

The movement of the shuttle clamping strips is effected as follows: As it is apparent from Figs. 4 and 5, the four boxes arranged at one side of the loom, are each provided with a strip 20 which usually bears strongly against the corresponding shuttle, when it enters the respective box. The strips are carried on a frame 19'. Said frame 19' is provided with dovetailed blocks 21, slidably within guides 22 fast to the shuttle boxes support. When it is desired to substitute a spent shuttle, it is necessary to release the strips 20 from the shuttles N. This release is effected by means of a fork 23, pivoted on frame 19' and passing with its two arms in the space between the first two and the last two strips 20. The two arms of said fork 23, terminate with two small bars 23' that pass beneath the four strips 20. On said fork there is also fastened the end of a flexible cable transmission 24, controlling the movement of said fork, the other end of the cable being fastened to lever 26, actuated by cam 27 (see Fig. 3). Upon said fork 23 being lowered through the actuation of transmission cable 24, its bars 23' slide over the inclined inside surface of strips 20 and force them to displace from their normal position, until they strike the stop rod 25, passing vertically above four strips. Thus the strips 20 have been displaced thereby releasing the shuttles N, and the strip frame 19' can now be lowered without being hindered by said strips. Shuttle N is thus freed and can be substituted as it will be explained later on.

Cam 16 rotating with shaft 15 acts on lever 17, pivoted at 18, which causes the lowering of rod 19, carrying the strip support constituted, as already mentioned, by frame 19'. In this way, under control of the members actuated by the two cams 16, and 27, the spent shuttle is freed.

At this time, the spent shuttle is ejected from its respective box. To this end, there is provided on shaft 15 a cam 29 acting on lever 30 and transmitting the movement to arms 31 and 32 which bring about the swinging of the expellers 33 of the shuttles which push it over an inclined tray 28 (see Fig. 3) that picks up the falling shuttle to forward it to the collecting box.

Successively, one of magazines 34 (see Fig. 3) and namely the one containing shuttles with the same thread colour as the spent shuttle, is lowered. Magazines 34 (see Fig. 3) are kept lifted by springs 35 and are connected with said springs and supported by means of a system of rods and links 36, 37, 38 and 39. Rods 39 terminate with small links 40 having their ends shaped in a suitable way, so as to allow the sliding over them of the head of the end of a rod 41 of a dobby, pivoted at 42, which receives its movement from arm 43 and lever 44, actuated by cam 45 already mentioned, and also keyed on shaft 15. The connecting rod 41 of the dobby oscillates within a slotted guide provided on the end of links 40 and receives its movement through a connecting rod 46 which is synchronized with the box movement whereby there is obtained the automatic selection of the colour. In this respect when the loom is stopped, the connecting rod 41 is arrested on the link controlling the lowering of the magazine containing the same colour as the shuttle to be replaced, whereby the cam 45 brings about the lowering of the wanted shuttle.

At this point, the transfer of the new shuttle from the magazine to the box is effected. For this purpose there

is provided an arm 47 which (see Figs 3 and 6) is in the rest position, in front of the magazines and receives the impulse through a system of levers 48, 49 and 50 actuated by cam 51, also keyed on shaft 15. Arm 47 terminates in a L-shaped holder 52, 53 (see Fig. 6) on which rests a vertical pushing blade 54, steadily maintained in its fully retracted position by a spring 55, coiled on a small stem 56 passing through a hole of the holder 53. A link 57 is pivoted on said stem and is articulated on an arm 47, so as to be pulled by a cable 58, the other end of which is fastened to lever 59 (see Fig. 3), one arm of which rests on cam 60 which is also keyed on shaft 15. Arm 47, while advancing, causes its flat portion 52 to strike against the last shuttle of the now lowered magazine so that same is taken out and carried to the mouth of the empty box C. At this instant cam 60 comes into action and, through lever 59, cable 58, arm 57 and stem 56 imparts to the vertical blade 54 a sudden forward motion so as to thrust the shuttle to rest on the bottom of the box i. e. in the working position.

As soon as this sequence of operation is completed, the loom is started again; to effect this, the angle lever 61, pivoted at 62 (see Figs. 3 and 7) is actuated by cam 63 which causes same to snap as soon as the operations of the different members are completed. Lever 61 ends with an articulated extension 64 hinged so as to be allowed to bend only forward, and is maintained in the upright position by a spring 65, assembled on the hinge pivot. Upon actuation, of lever 61, its extension 64 strikes against the wing 14 thus causing the rotation of shaft 7, thereby starting the loom and stopping the mechanism concerning the replacement of the shuttle. In the back travel to the rest position, extension 64 of lever 61 strikes against wing 14 but can by-pass same as it can yield thanks to its articulation. Any hindrance that might happen in the loom during the substitution of the shuttle causes the automatic stopping of the whole loom by means of already known devices, that are therefore not described further.

Of course, as already mentioned, all the parts now described are illustrated in the way of example and the ensemble of the machine may vary in its design without therefore departing from the scope of the present invention.

What I claim is:

1. In a shuttle changing loom having a lay operating with a plurality of weaving shuttles, each having a thread of a different colour from the others, a plurality of first shuttle boxes disposed on one side of the loom, a similar number of second shuttle boxes disposed on the opposite side of the loom, said first and second shuttle boxes receiving the shuttles, shuttle magazines mounted at the side of the loom with the second shuttle boxes, means associated with each shuttle for indicating when the shuttle is spent, electromagnetic means responsive to said foregoing means for automatically stopping the loom, means associated with the second shuttle boxes for freeing and ejecting the spent shuttle from its associated second shuttle box, means for transferring a full shuttle, carrying thread 50 of the same colour as that carried by the spent shuttle, from the magazine to the box vacated by the spent shuttle, means for restarting the loom when the replacement shuttle is in the box and motor driven cam means actuated by said electromagnetic means for sequentially actuating said last three mentioned means.

2. In a shuttle changing loom having a lay operating with a plurality of weaving shuttles, each having a thread of a different colour from the others, a plurality of first shuttle boxes disposed on one side of the loom, a similar number of second shuttle boxes disposed on the opposite side of the loom, said first and second shuttle boxes receiving the shuttles, shuttle magazines mounted at the side of the loom with the second shuttle boxes, means associated with each shuttle for indicating when the shuttle is spent, electromagnetic means responsive to said fore-

going means for automatically stopping the loom, means associated with the second shuttle boxes for freeing and ejecting the spent shuttle from its associated second shuttle box, means for transferring a full shuttle, carrying thread of the same colour as that carried by the spent shuttle, from the magazine to the box vacated by the spent shuttle, means for restarting the loom when the replacement shuttle is in the box and means actuated by said electromagnetic means for sequentially actuating said last three mentioned means, said actuating means including a motor driven 10 rotating cam shaft and cams arranged thereon for successive operation with a cam sequentially actuating each of said last three mentioned means.

3. A device as claimed in claim 2, wherein clamping blades are mounted in each of the second boxes to arrest 15 the shuttles, a frame supporting the blades in the boxes, and means slidably mounting the frame, said last means sliding responsive to said freeing and ejecting means to free the spent shuttle.

4. A device as claimed in claim 3, wherein said means for freeing and ejecting the spent shuttle includes a member connected to the blades to free the blades from the spent shuttles and connected to the frame to slide the frame relative to its box.

5. A device as claimed in claim 2, wherein said freeing 25 and ejecting means includes an inclined tray communicating with the boxes, an expeller for pushing the spent shuttle into the tray and lever means actuated by one of the cams on the camshaft for operating the expeller.

6. A device as claimed in claim 2, wherein the transferring means includes means normally supporting the magazines above the loom, and means for lowering the magazine containing the shuttle with the desired color under actuation of one of the cams.

7. A device as claimed in claim 6, wherein the transferring means further includes a pusher blade actuated by one of the cams, an arm actuated by another of the 35

5

6

cams, flexible means connecting the said cam and arm and moving said arm to eject the desired shuttle from the magazine, said pusher blade thrusting the shuttle into the box vacated by the spent shuttle.

8. A device as claimed in claim 6, wherein said means for restarting the loom includes a lever having a pivoted extension, means connecting one of the cams with the lever so that rotation of the cam moves the lever, a starting rod for the loom and an offset on the rod against which the extension strikes as the lever is moved to start the loom, the extension moving freely back to its normal position.

9. A device as claimed in claim 2, wherein the means for sensing when a shuttle is spent includes an oscillating lever connected to the control members of the lay and actuated thereby, said electromagnetic means being secured to the lever, a second lever, a cable transmission, means responsive to said electromagnetic means for rotating the second lever, which actuates the cable transmission and means responsive to the operation of the cable transmission for rotating the cam shaft.
